Patented Apr. 10, 1917.

UNITED STATES PATENT OFFICE.

LEWIS C. BAYLES, OF EASTON, PENNSYLVANIA, ASSIGNOR TO INGERSOLL-RAND COMPANY, OF JERSEY CITY, NEW JERSEY, A CORPORATION OF NEW JERSEY.

VALVE FOR PERCUSSIVE TOOLS.

1,222,353.

Specification of Letters Patent. Patented Apr. 10, 1917.

Application filed March 6, 1915. Serial No. 12,680.

To all whom it may concern:

Be it known that I, LEWIS C. BAYLES, a citizen of the United States, residing at Easton, in the county of Northampton and State of Pennsylvania, have invented a certain new and useful Improvement in Valves for Percussive Tools, of which the following is a specification.

This invention relates to fluid operated percussive tools, and more particularly to tools of the type wherein the piston has two rearward pressure surfaces and one forward pressure surface, one of the rearward pressure surfaces being subjected to constant pressure and the other two surfaces being subjected to intermittent pressure.

The object of the present invention is to provide a tool of this type in which the admission of fluid to the intermittently supplied rearward surface of the piston is controlled by a valve whereby the admission of fluid to this surface is continued for a longer time during the forward stroke than during the rearward stroke of the piston, an increase in power and efficiency being thus obtained. This object is secured by the invention, a practical embodiment of which is shown in the accompanying drawings, in which,

Figures 1 and 2 show diagrammatic representations of the tool with the moving parts in different positions, and,

Fig. 3 shows the valve 10 in detail.

The tool, as shown, comprises a cylinder 1, in which is a forward cylinder bore 2 of large diameter and a rearward cylinder bore 3 of smaller diameter. Sliding in the cylinder 1 is a piston which has a head 4 fitting the forward bore 2 and a smaller shank 5 fitting the rearward bore 3. The operating fluid is admitted constantly to the rearward end of the bore 3 through an inlet passage 6. To supply fluid for the rear end of the forward bore 2 a passage 7 leads to a chamber 8 from the forward face of which a passage 9 leads to the rearward end of the bore 2. To control the passage 9 a valve 10 is provided. This valve 10 slides in a bore extending rearwardly from the chamber 8 and has a forward portion 11 of smaller diameter which serves to control the rearward opening of passage 9, and a rearward portion or head 12 of larger diameter which slides in a bore or closed cylinder 13. From the side of bore 3 at a point uncovered

by the shank of the piston soon after it starts to move forward, a port 14 leads to the rear end of bore 13, while a leak passage 15 of smaller size than the port 14 leads to the atmosphere from the rear end of bore 13. A similar leak port 16 also leads to atmosphere from the forward end of bore 13. To convey fluid to the forward end of the bore 2 a passage 17 is provided which leads from a point in the side of the bore 3 uncovered by the piston near the end of its forward stroke to the forward end of the bore 2. To exhaust the fluid from the front and rear ends of the bore 2 a main exhaust passage 18 and two auxiliary exhaust passages 19 and 20 are provided, these auxiliary exhaust passages 19 and 20 being controlled by an exhaust valve 21, the details of this exhaust controlling mechanism forming no part of the present invention, being fully described in the co-pending application of F. M. Slater, Serial No. 879,860, filed December 31st, 1914.

In the operation of the tool, supposing the parts to be in the positions shown in Fig. 2, fluid is being admitted to the rear of bore 2 through the passage 7, chamber 8, and passage 9, the valve 10 being in its rearmost position on account of the pressure exerted on its front surface by the fluid in the chamber 8, the port 14 at this time being closed by the piston shank 5. The exhaust valve 21 will be in the position shown, cutting off the exhaust from the rear end of the bore 2. As the piston moves forwardly, the rear end of the shank 5 will uncover the port 14 after the piston has traveled but a short distance. This will admit pressure to the rear end of the bore 13, and as the rear surface of the valve 10 is larger than its forward surface, the valve 10 will be moved forwardly, cutting off the opening to passage 9 from the chamber 8, and thus cutting off the admission of fluid to the rear end of the bore 2. The piston will continue to move forward under the constant pressure on the rear surface of the shank 5 and the expansion of the fluid in the rear end of the bore 2. When the rear end of the shank 5 uncovers the rearward opening of the passage 17, fluid will be admitted from the bore 3 into the forward end of bore 2, at the same time the rear edge of piston head 4 will uncover the main exhaust passage 18. This will move the exhaust valve 21 to the

- position shown in Fig. 1, allowing the fluid to escape freely from the rear end of the bore 2, after the main exhaust 18 has been closed by the piston on its backward stroke.
5. The piston will now move rearwardly, the fluid in the forward end of the bore 2 acting expansively when the admission through the passage 17 is cut off. The valve 10 will remain in the position shown in Fig. 1 until after the rear end of the shank 5 closes the port 14. When this port 14 is closed the pressure on the rear surface of the valve will fall due to the fluid escaping through the leak port 15. As the only force tending 10 to move the valve rearwardly is the pressure of the fluid in chamber 8 against the small annular shoulder on the forward portion of the valve 10, the pressure in the rear end of the bore 13 will have to fall almost to atmospheric pressure before the valve 10 will start to move, this pressure being reached before the piston reaches the end of its stroke, but when the valve is once started the intake pressure will be exerted 15 on the whole forward face of the valve 10, causing the valve to complete its travel very quickly. The exhaust valve 21 will moreover be shifted by the escaping fluid so as to close the exhaust passage 19 as soon as 20 the pressure in passage 20 is relieved by the piston head 4 uncovering the main exhaust 18, thus causing compression between the piston head 4 and the end of the cylinder which will be exerted on the forward surface of portion 11 of the valve and will insure the valve opening before the piston reaches the end of the cylinder. The leak port 16 is provided to allow the valve 10 to have free movement in either direction, 25 as far as any pressure in the forward end of the bore 13 is concerned. It will be seen that by this construction, although the valve 10 moves forward to close off the passage 9 immediately the port 14 is uncovered by 30 the piston during its forward stroke, the movement of the valve 10 rearwardly when the port 14 is again covered by the piston on its rearward stroke will be subject to a lag due to the fact that the fluid in the rear end of the bore 13 must escape to the atmosphere. The movement of the valve thus permits the admission of fluid to the rear end of the bore 2 to be continued longer 35 during the forward stroke of the piston than during the rearward stroke, a greater power in the operation of the tool being thereby obtained.
- It is to be understood that while the present showing and description discloses only 40 one specified modification of the present invention, other forms and modifications are included in the spirit and scope of the same, as expressed in the appended claims.
- 65 What I claim is:
1. In a fluid operated percussive tool, a cylinder, a piston therein having two rear pressure surfaces and one forward pressure surface, means for admitting fluid to the cylinder to exert a constant pressure on one of said rearward surfaces, a conduit independent of the piston for conveying fluid to exert an intermittent pressure on the other of said rear pressure surfaces, a valve controlling said conduit, a conduit controlled by said piston for conveying fluid to exert an intermittent pressure on the forward surface of said piston and exhaust means for the intermittently supplied portions of the cylinder.
2. In a fluid operated percussive tool, a cylinder, a piston therein having two rear pressure surfaces and one forward pressure surface, means for admitting fluid to the cylinder to exert a constant pressure on one of said rearward surfaces, a conduit independent of the piston for conveying fluid to exert an intermittent pressure on the other of said rear pressure surfaces, a valve controlling said conduit, a conduit controlled by said piston for conveying fluid to exert an intermittent pressure on the forward surface of said piston and exhaust means for the intermittently supplied portions of the cylinder, comprising an independent exhaust valve.
3. In a fluid operated percussive tool, a cylinder having a larger forward bore and a smaller rearward bore, a piston having a head fitting said larger bore and a shank fitting said smaller bore, an inlet for admitting fluid constantly to the rear end of said smaller bore, a passage independent of the piston from said inlet to the rear end of said larger bore, a valve controlling said passage to admit fluid to the rear end of said larger bore only near the rearward end of the piston stroke, means for conveying fluid intermittently to the forward end of said larger bore, and means for exhausting the intermittently supplied portions of the cylinder.
4. In a fluid operated percussive tool, a cylinder having a larger forward bore and a smaller rearward bore, a piston having a head fitting said larger bore and a shank fitting said smaller bore, an inlet for admitting fluid constantly to the rear end of said smaller bore, a passage independent of the piston from said inlet to the rear end of said larger bore, a valve controlling said passage to admit fluid to the rear end of said larger bore only near the rearward end of the piston stroke, means for conveying fluid intermittently to the forward end of said larger bore, and means for exhausting the intermittently supplied portions of the cylinder comprising an independent exhaust valve.
5. In a fluid operated percussive tool, a cylinder having a larger forward bore and a smaller rearward bore, a piston having a

- head fitting said larger bore and a shank fitting said smaller bore, said piston having two rearward pressure surfaces and a forward pressure surface, means for admitting 5 fluid constantly to exert a pressure on one of said rearward pressure surfaces, a passage independent of the piston from the constant pressure portion of the cylinder to convey fluid to exert pressure on the other 10 of said rearward pressure surfaces, a valve controlling said passage, means for moving said valve to open said passage near the end of the rearward stroke of said piston, and to close said passage after said piston 15 has traveled forward a short distance on its forward stroke, means for intermittently conveying fluid to the forward end of the cylinder and means for exhausting said intermittently supplied cylinder portions. 20 6. In a fluid operated percussive tool, a cylinder having a smaller rearward bore and a larger forward bore, a piston having a head fitting said larger bore and a shank fitting said smaller bore, means for constantly admitting fluid to the rear end of 25 said smaller bore, a conduit independent of the piston from the rear end of said smaller bore to the rear end of said larger bore, a valve for controlling said conduit, having 30 operating surfaces, a port opened by said piston for conveying fluid to an operating surface of said valve to move said valve to close said conduit when said piston has traveled a short distance on its downward stroke, 35 means for moving said valve to open said conduit near the rear end of said piston rearward stroke, means for conveying fluid intermittently to the forward end of said larger bore and means for exhausting fluid 40 from the ends of said larger bore. 7. In a fluid operated percussive tool, a cylinder having a smaller rearward bore and a larger forward bore, a piston having a head fitting said larger bore and a shank fitting 45 said smaller bore, means for constantly admitting fluid to the rear end of said smaller bore, a conduit independent of the piston from the rear end of said smaller bore to the rear end of said larger bore, a valve 50 for controlling said conduit, having operating surfaces, a port opened by said piston for conveying fluid to an operating surface of said valve to move said valve to close said conduit when said piston has traveled a short distance on its downward stroke, means for moving said valve to open said conduit near the rear end of said piston rearward stroke, means for conveying fluid intermittently to the forward end of said larger bore and means for exhausting fluid from the ends of said larger bore.
- for conveying fluid to an operating surface of said valve to move said valve to close said conduit when said piston has traveled a short distance on its downward stroke, 55 means for moving said valve to open said conduit near the rear end of said piston rearward stroke, means for conveying fluid intermittently to the forward end of said larger bore and means for exhausting fluid 60 from the ends of said larger bore, comprising a separate fluid controlled exhaust valve. 8. In a fluid operated percussive tool, a cylinder having a two diameter bore, a piston having a head fitting the larger bore and a shank fitting the smaller bore, an inlet for admitting fluid constantly against one face of said piston to drive the piston in one direction, a conduit independent of the piston for conveying fluid to exert an intermittent pressure on another face of the piston to drive it in the same direction as the constant pressure, a valve controlling said conduit, a conduit controlled by the piston for intermittently conveying fluid to a piston face opposed to the said two faces and exhaust means for relieving the pressure from the intermittently supplied faces of the piston. 70 9. In a fluid operated percussive tool, a cylinder, a piston therein having two pressure surfaces facing the same way, and an opposed pressure surface facing the opposite way, means for admitting fluid to the cylinder to exert a continuous pressure on 80 one of said two piston surfaces, a conduit independent of the piston for conveying fluid to exert an intermittent pressure on the other of said two piston surfaces, a valve controlling said conduit, a conduit controlled by the piston for conveying fluid to exert an intermittent pressure on the opposed piston surface and exhaust means for the intermittently supplied portions of the cylinder. 85 90 95
- In testimony whereof, I have hereunto set my hand.
